UNITED STATES PATENT OFFICE

96,521

DESIGN FOR A THERMOMETER

Walter von Nessen, New York, N. Y., assignor to
Testrite Instrument Co., New York, N. Y., a
copartnership composed of Herman Neuwirth
and Jacob Bernstein

Application May 7, 1935, Serial No. 56,713

Term of patent 14 years

To all whom it may concern:

Be it known that I, Walter von Nessen, a citizen
of the United States and a resident of the city,
county, and State of New York, have invented a
new, original, and ornamental Design for Ther-
mometers, of which the following is a specification,
reference being had to the accompanying draw-
ing, forming part hereof.

In the drawing, Figure 1 is a front elevation of
a thermometer embodying my new design, and
Figure 2 is a side elevation thereof.

I claim:

The ornamental design for a thermometer, as
shown.

WALTER VON NESSEN.
